STOCKING

Claude Shelton, Reading, Pa.

Application March 24, 1949, Serial No. 1,601

Term of patent 14 years

(Cl. D47—7)

To all whom it may concern:

Be it known that I, Claude Shelton, a citizen of the United States, residing at Reading, in the county of Berks and State of Pennsylvania, have invented a new, original, and ornamental Design for a Stocking, of which the following is a specification, reference being had to the accompanying drawing, forming part thereof.

Fig. 1 is a conventional side view of a stocking showing my new design, and

Fig. 2 is a perspective view, on an enlarged scale, of the front portion of the stocking shown in Fig. 1, as expanded on the foot of a wearer, and showing my design as in Fig. 1.

The characteristic feature of my design resides in the combination on the stocking disclosed of

the specific lace knitted ankle band which abuts the upper edge of the heel splice as shown.

I claim:

The ornamental design for a stocking, as shown and described.

CLAUDE SHELTON.
